OTOSCOPE

Arthur J. Pulos, Fayetteville, N.Y., assignor to Welch Allyn, Inc., Skaneateles Falls, N.Y., a corporation of New York

Filed Nov. 26, 1965, Ser. No. 88,224

Term of patent 14 years

(Cl. D83—12)

FIGURE 1 is a front elevational view of an otoscope embodying my new design and showing the proximal side of the head portion thereof;

FIGURE 2 is a side elevational view thereof;

FIGURE 3 is a fragmentary elevational view of the other side thereof, the omitted portion being the mirror image of the same portion shown in FIGURE 2;

FIGURE 4 is a fragmentary rear elevational view thereof, the omitted portion being identical with the same portion shown in the other figures.

I claim:

The ornamental design for an otoscope, as shown and described.
